UNITED STATES PATENT OFFICE.

JAMES T. SIBLEY AND CHARLES E. WALDORF, OF PATERSON, NEW JERSEY; SAID WALDORF ASSIGNOR TO SAID SIBLEY.

TONE ARM.

Application filed April 24, 1919. Serial No. 292,332.

To all whom it may concern:

Be it known that we, JAMES T. SIBLEY and CHARLES E. WALDORF, citizens of the United States, residing in the city of Paterson, county of Passaic, and State of New Jersey, have invented certain new and useful Improvements in Tone Arms, set forth in the annexed specification.

Our present invention relates to an improved tone arm for use in connection with the stop device described in the application of James T. Sibley, Serial No. 202,772, filed November 19th, 1917, and in fact is intended as a substitute for the tone arm of such prior application.

In the accompanying drawings—

Fig. 1 is a longitudinal section of the tone arm and sound box extension.

Fig. 2 is a plan view of the same with the adapter extension arranged in position to reproduce records of the gramophone type.

Fig. 3 is a side elevation of the tone arm with the sound box extension and adapter arranged for use in connection with records of the so-called Pathé type.

Fig. 4 is a similar view with the sound box extension and adapter arranged for use in connection with the so-called Edison type.

Fig. 5 is an enlarged view of the oscillating sound box extension with the adapter detached therefrom.

Fig. 6 is an end view showing the stop projections upon the coupling end.

Fig. 7 is a side elevation of the adapter elbow.

Fig. 8 is an end view of the same showing the stop notches.

Fig. 9 is an opposite end view of the elbow showing the stop notches.

Fig. 10 is a side elevation of the sound box elbow.

Fig. 11 is an end view showing the relative location of the stop projections.

Fig. 12 is a rectified section of the stop projections upon the oscillating arm shown in Fig. 5, and the notches in the upper end of the elbow illustrated in Fig. 7.

Fig. 13 is a similar diagrammatic rectified view of the notches and stop projections on the opposite end of the elbow illustrated in Fig. 7, and also of the sound box elbow illustrated in Fig. 10.

Similar reference numerals refer to like parts throughout the specification and drawings.

The tubular standard 1 is designed to be mounted upon the upper side of a phonograph cabinet and serves as an element of the sound tube. It is secured to the cabinet top 2, by means of the flange 3. An annular shoulder 4, is formed by reducing the diameter of the upper part of the standard so as to form a ball-race for the balls 5. Within the tubular standard, and cast integral therewith is a spider 6, which serves as a support for the sheave 7, the purpose of which will be hereafter explained. Surrounding the upper reduced portion of the standard 1, is a sleeve 8, the lower end of which is shouldered to bear upon the balls 5. In the upper end of this sleeve is a ball-race shoulder 9, upon which the series of balls 10 is located. Within this enlarged upper end of the sleeve 8, the section 11 is inserted and rigidly secured in any convenient manner, as by means of a series of screws 12'. The balls 10, are located in the race formed by the lower end of the section 11 and the shoulder 9. The peripheries of said balls are designed to contact with the upper end of the standard 1, so that the sections 8 and 11, swing about the standard 1 with very little friction.

In the section 11 is secured a bracket 12, which carries a sheave 13. The outer free end of the section 11 is provided with a downward extension 14, which is provided with a hook-shaped bearing upon its inside to receive a tongue 15, upon the tone arm section 16, which latter has its mating end of general spherical form, as at 17, so as to form a substantially sound proof joint between the mating ends of the sections 11 and 16, the construction being such that the extension 16 may oscillate vertically about the bearing 14-15, as a pivot. Within this end is rigidly secured a cross-piece 18, either by riveting or soldering, or any convenient manner to permanently secure said piece in place. The chain, or cable 19, is connected to the upper end of the cross-piece 18, and passes over the sheave 13, upon the inside of the section 11, thence downwardly and over the sheave 7, thence horizontally to the stop mechanism of the device of the said prior application (not shown). The chain, or

cable 19, is under a slight tension, as by the spring 19' insufficient normally in itself to hold the section 16 in axial alignment with the horizontal part of the section 11. However, with the stop and repeat mechanism of said prior application devices are described for placing the cable 19, under a greater tension so that the section 16 may be elevated automatically, so as to raise the sound box clear of the record, shift it to initial playing position and then lower it upon the record. Such devices, however, form no part of our present invention.

The outer end of the section 16 is downwardly and forwardly extended and provided with a reduced thimble as at 20, over which the upper end of the elbow 21 may be slipped. The angularity of the elbow 21 is such that when in the position indicated in Figs. 1 and 2, the axis of the lower part of the elbow will lie in a vertical plane and be parallel to the axis of the section 16. The shoulder 22, of the section 16, is provided with V-shaped projections 23—24, and also the square projection 25. The upper end of the elbow 21 is provided with an enlarged collar 26, the internal diameter of which is sufficient to overlap the larger diameter of the angular end of the section 16. In the bottom of the race formed by this collar we provide a series of notches, as 27, 28, 29, 30, 31, 32. On reference to Fig. 12, it will be noted that the notches 27—28 have square shoulders upon the one side and inclined shoulders upon the other side; while the metal between the notches is cut away as at 27'. The notches 29, 30, 31 and 32 are all V-shaped notches.

Referring now to Fig. 12 it will be noted that if the elbow 21 is moved up into contact with section 16, the projection 25 will take into the notch 27, while the projection 24 will take into the notch 29, and projection 23 into the notch 31. If now, the elbow 21 is moved to the left the projection 25 will rise up on the inclined side wall of the notch 27 and the projections 24 and 23 will correspondingly ride up on the inclined side walls of the notches 29 and 31, until such time as the projection 25 comes to the notch 28, and simultaneously the notches 24 and 23, respectively, come into registry with notches 30 and 32, when, of course, the elbow 21 will be in position to slide axially on the thimble 20 to the depth permitted by the series of notches in said elbow in connection with the mating projections 23, 24 and 25. In other words, the rotation of the elbow 21 upon the thimble 20 is attended by a longitudinal movement of said elbow on the thimble to the extent of the depth of the series of notches 27, 28, 29, 30, 31 and 32. The rotation of the sound box thimble 33 upon the opposite end of the elbow 21, is attended with the same results. The elbow 33 is pro-

vided with the square projection 34, and the V-shaped projections 35—36, to co-operate with the notches 37, 38, 39, 40, 41 and 42 respectively.

Within the end of the extension 16 is a cross-piece 43, rigidly secured in place, and within the elbow 33, a similar cross-piece 44, is rigidly secured. Connecting these cross-pieces 43 and 44, is a tension spring 45, the purpose of which is to yieldingly hold the three elements 16, 21 and 33 together and yet permit the relative rotation of the elbow 21 upon the thimble 20, and also permit the elbow 33 to turn upon the elbow 21; but the rotation of the elbow 21 upon the thimble 20 is affected by a longitudinal movement of the elbow 21 upon the axis of the thimble 20, due to the rise of the projections 23, 24 and 25 out of the notches 27, 29 and 31, and the riding of said projections upon the flat portions between said notches until the projection 25 reaches the notch 28, and the projection 24 correspondingly reaches the notch 30, and the projection 23 reaches the notch 32, when the spring 45 will cause the two parts to snap together and be held against accidental rotation. Similarly the same spring 45, being connected to the cross-piece 44, will permit the elbow 33 to be turned within the elbow 21 with its projections 34, 35 and 36 rising out of the notches 37, 39 and 41, against the tension of the spring 45, when of course, the elbow 33 may be turned upon the common axis of the two elbows until such time as the projections 34, 35 and 36 drop into the notches 38, 40 and 42 respectively.

The square shoulder notches 27 and 28, in one end of the elbow 21, and the square shoulder notches 37 and 38 in its opposite end serve to limit the rotational movement of the parts, for it will be seen that the limit of movement of the projection 25 is between the notches 27 and 28, and correspondingly the limit of movement of the elbow 33 and its projection 34, will be the square shoulder notches 37 and 38. Thus it will be seen that the extension 16 is provided with the adapter elbows 21 and 33, whereby the three several positions of the sound box may be assumed as indicated in Figs. 1, 3 and 4; that is, with the plane of the diaphragm of the sound box vertical, as in Fig. 1, or inclined to the plane of the record, as in Fig. 3, or parallel to the plane of the record, as in Fig. 4.

From a reference to Figs. 1 and 4, it will be noted that the elbow 33 is turned through an angle of 90 degrees in order that the sound box S may occupy the positions shown in the two figures and that the axes of the elbow 21 lie in a common vertical plane. This being the case the stop notches 37 and 38 are located circumferentially with their centers 90 degrees apart. Similarly the notches 39 and 40 are 90 degrees apart, and

the notches 41 and 42 are also 90 degrees apart; thus it will be seen that the limit of throw for the elbow 33 is but 90 degrees.

From the position illustrated in Figs. 1 5 and 2, it will be noted that the elbow 21 must be turned upon the diagonal axis in order that the sound box may assume the position illustrated in Fig. 3.

With the projections 23, 24, and 25, 120 10 degrees apart, we find that the correct distance for the pairs of notches 27 and 28, 29 and 30, 30 and 31, will be 103 degrees apart respectively. When these angularities of notches are selected, as above indicated, and 15 the elbows are turned, as shown in the drawings, it is found that the plane of the diaphragm of the sound box will assume in each case, the correct playing position for the three types of records now most generally in use.

The provision of the internal spring 45 makes the use of external locking devices for the adjustable sound box end of the tone arm unnecessary, while it also serves to 25 firmly hold the parts in their adjusted positions and prevents any tendency to shift from those positions in use.

The depression 27' between the notches 27 and 28, and the depression 37' between 30 the notches 37 and 38, permit us to utilize the end walls of the notches 27—28 and 37—38 as stops to limit the angularity of the two elbows 21 and 33. It will be noted that the depths of the notches 29, 30, 31 and 32 are 35 the same as the depths of the notches 27—28 below the depressed portion 27'. Similarly the depths of the notches 39, 40, 41 and 42 are the same as the depths of the notches 37 and 38 below the depression 37'. In 40 this manner the elbows 21 and 33 may be turned upon their respective axes without binding or tilting of said elbows out of their axial alignment with each other and with the axis of the thimble 20.

45 It will thus be seen that we have provided a tone arm and sound box adapted which is a distinct improvement over the tone arm shown in the prior application above referred to; that the tone arm and sound box 50 extension is so constructed that the chain, or cable 19, of said prior application, is completely enclosed within the tone arm and is therefore not liable to disarrangement when in use.

55 We have shown in Figs. 1 and 2 the segmental gear 50 as integral with the sleeve 8, said segmental gear being utilized for the same purpose as indicated in the above

named prior application, and utilized in connection with the stop and repeat mechanism therein described.

In order to lock the sleeve 8 to the tubular standard 1, and yet permit the tone arm to swing freely in a horizontal plane within the necessary limits, we provide the tubular standard 1 with a circumferential slot 47, into which the point of the screw 46 enters, said screw being inserted in the sleeve 8.

We claim:

1. In a tone arm, the combination of a swinging sound tube, a sound box section pivoted upon the free end of said tube for vertical oscillation, a chain or cable within said tube and connected to said sound box section above its pivot for vertically elevating said sound box section.

2. In a tone arm, the combination of a horizontally swinging sound tube section, a sound box section having its axis normally in alignment with the axis of said sound tube and pivoted thereto at a point below said axes, and a chain or cable connected to said sound box section at a point above its pivot end extending through the interior of said sound tube, whereby said sound box section may be elevated as and when said chain or cable is put under tension.

3. In a tone arm, the combination of a sound tube section mounted to swing in a horizontal plane, a sound box section having an offset pivotal connection with said sound box tube section whereby said sound box section may oscillate in a vertical plane, a chain or cable connected to said sound box section above its pivot and extended through the interior of said sound tube section, and means for putting said cable under a normal tension whose tendency is to 90 elevate said sound box section.

4. In a tone arm for talking machines, the combination of three tubular members arranged in end to end relation, mating notches and projections respectively upon the adjacent ends of said members, a spring within and connecting the adjacent ends of the two non-adjacent members, for yieldingly holding the three members in frictional end to end engagement but permitting the turning of each member upon its next adjacent member to shift the relative engagement of their respective mating notches and projections.

JAMES T. SIBLEY.

CHARLES E. WALDORF.
